UNITED STATES PATENT OFFICE

WALTER KUSCHE, OF BERLIN-CHARLOTTENBURG, RUDOLF DAHMS, OF CHARLOTTENBURG, AND FRITZ PFLEIDERER, OF BERLIN-CHARLOTTENBURG, GERMANY, AS-
SIGNORS TO SIEMENS & HALSKE AKTIENGESELLSCHAFT, OF SIEMENSSTADT, NEAR
BERLIN, GERMANY, A COMPANY OF GERMANY

TELEPHONE SYSTEM

Application filed December 12, 1928, Serial No. 325,534, and in Germany December 15, 1927.

This invention relates to telephone systems and particularly to systems in which communication channels involving speech amplifiers or repeaters are built up by automatic switches responsive to dial impulses.

5 It is an object of this invention to render speech amplifiers accessible over automatically established connections commonly available to a plurality of lines of different characteristics.

10 A feature of the invention is a means for automatically adjusting the characteristics of the speech amplifier taken for use to the characteristics of the line. Each amplifier has associated with it an automatic switch which is set into operation upon the seizure of the amplifier and which then automatically moves into a particular position corresponding to the line from which the connection is extended and in which position artificial networks corresponding to the characteristics of such line are appropriately connected to the amplifier.

15 In accordance with another feature of the invention the amplifier is properly adjusted in the manner set forth in accordance with the characteristics of both the calling and the called line.

20 In accordance with a further feature of the invention the calling lines are divided into groups and in each group all the lines have the same characteristics so that the amplifier is adjusted in accordance with the group from which the call originates.

25 The drawings consist of three sheets designated Fig. 1, Fig. 2 and Fig. 3 and when placed as indicated in Fig. 4 diagrammatically illustrate the essential features of the invention. Fig. 2a represents circuits and apparatus identical with those of Fig. 2 and Fig. 3a represents circuits and apparatus identical with those of Fig. 3.

30 The calling lines are arranged in groups wherein each line of a group has the same characteristics as each other line of that group and the lines of one group may differ in their characteristics from the lines of other groups. In this manner switch 1 having arms 2, 3 and 4 is accessible through any well known line switch or line finder arrangement

to lines of one characteristic and the switch 5 having arms 6, 7 and 8 is accessible to lines of another characteristic. Only one level of such switches is here represented, it being understood that the same or similar wiring arrangements are made in other levels, that the different levels are directly selected and that the contacts in each level are automatically selected.

35 The first contacts of the banks of these selectors, as shown, are multiplied together and extend to a secondary selective switch. Thus the first contacts of the banks traversed by arms 2 and 6 are connected together and extend to arm 9 of switch 12 and the first contacts of the banks traversed by arms 3 and 7 are connected together and extend to arm 10 of switch 12. The first contacts of the banks traversed by the corresponding testing arms 4 and 8 are not multiplied, as usual, 40 but lead to a series of relays 13 and 14, respectively. Thus when the arm 4 is set on its first contact, a circuit will be completed to the winding of relay 13, whence the circuit will extend over the normal contacts of the 45 inner right hand armature of relay 13, the back contact and left hand armature of relay 13, the back contact and left hand armature of relay 14, the back contact and left hand armature of relay 15, the winding of relay 16, to ground. Since a battery connection 50 (not shown) is made over the arm 4, relays 13 and 16 will be operated. Relay 13 will then lock through its alternate contact and inner right hand armature directly to the 55 winding of relay 16 and the chain circuit through the left hand armatures of this series of relays will be broken. Hence, another selector, such as 5, testing its first contacts will find a busy condition denoted by 60 the absence of the ground connection to the contact traversed by arm 8. As long as the selector 1 remains set on its first contacts, relay 13 individual to switch 1 will remain 65 operated in series with relay 16 which is individual to switch 12 and no other selector, such as 1 or 5, can gain access to the selector 12.

70 In a similar manner the second contacts of the selectors 1 and 5 are multiplied together 75

and lead to a secondary selector 17, having arms 18, 19 and 20. Likewise, the second contacts traversed by the testing arms 4 and 8 are connected to a series of relays 21, 22 and 23 controlling a relay 24 individual to selector 17. Thus it will be seen that a call coming in over either selector 1 or 5 will be automatically extended in the first instance to selector 12 and the first contacts in the 10 banks of the remaining switches of this group will be rendered busy by the breaking of the chain circuit through relays 13, 14 and 15. Similarly, it will be noted that the next call coming in over either of such first 15 selectors will be automatically extended to selector 17 and thereafter the second contacts in the banks of the remaining first selectors will be rendered busy by the breaking of the chain circuit through the left hand 20 armatures of relays 21, 22 and 23.

Each of the secondary selectors 12 and 17 is shown with two levels, it being understood, as before, that the different levels are directively selected and the contacts in the levels 25 are automatically selected. In the present case the first contacts in each level shown and in each switch shown are multiplied together and lead to a single speech amplifier. The testing contacts, however, are not multiplied but have individual conductors extending therefrom to a plurality of relays in a number of chain circuits, somewhat in the same manner as in connection with the first 30 selectors. Thus when either of the secondary 35 selectors has been directively set on either of its two levels shown and has then automatically selected its first contact, one of the relays 25 to 29 will be operated in series with relay 30 and by opening a chain circuit including the outer left hand armature and back contact of one of such chain relays will prevent any other selector from appropriating the same speech amplifier. In a similar manner when the first contacts of 40 the secondary selectors are passed over and a set of second contacts are selected, then a relay within Fig. 2a similar in all respects to one of the chain relays 25 to 29 will be operated in series with a relay similar to 45 relay 30 and the chain circuit controlled thereby will be opened and the second contacts traversed by arms 11 and 20 will be marked as busy.

Now by the combination of the third wire 50 testing relays which are operated the characteristics of the calling line will be known at the speech amplifier. Let it be assumed that the secondary selector 12 has been first selected and that thereafter the conductors 55 60 65 70 75 80 85 90 95 100 105 110 115 120 125 130 135 140 145 150 155 160 165 170 175 circuit from ground, outer right hand armature and front contact of relay 26, conductor 32, normal contacts of the left hand armature of relay 33, and in parallel therewith, normal contacts of the right hand armature 70 of relay 34, to conductor 35 and thence through the winding of relay 36 to battery and ground. Relay 36 becomes energized and attracts its armatures.

The speech amplifier shown in Fig. 3 consists essentially of repeating coils 38 and 39 and amplifiers 40 and 41, here shown schematically but representing a device of the character disclosed in Patent 1,216,136, granted to B. W. Kendall. Associated with the incoming end are a plurality of artificial networks 42 and 43 connected to the speech amplifier by an automatic switch 44 having arms 45 to 48, inclusive, and a stepping magnet 49. Also associated with the incoming end of this speech amplifier is a connecting switch 50 having arms 51 to 56, inclusive, and a stepping magnet 57. This switch serves to extend the conductors 31 to the incoming end of the speech amplifier through various types of attenuating networks shown connected to the contacts traversed by arms 51 to 54, inclusive.

Should the incoming call have originated in the group of lines served by switch 1, then according to our assumptions, relay 13 will be energized. Therefore, a circuit will be extended from ground, the armature and back contact of relay 16, the armature and back contact of relay 58, winding of relay 59, outer right hand armature and front contact of relay 13, front contact and innermost armature of relay 36, conductor 60 to the first contacts traversed by arm 55 of switch 50 and arm 47 of switch 44.

Upon the operation of relay 30, hereinbefore described, a connection will be established from ground, interrupter 61, conductor 62, back contact and right hand armature of relay 33, armature 63 of relay 30, and the front contact associated therewith, winding of stepping magnet 57 to battery and ground. At the same time a circuit is established from ground, interrupter 61, conductor 62, back contact and left hand armature of relay 34, front contact and armature 64 of relay 30, winding of stepping magnet 49, to battery and ground. Under the control of interrupter 61, both switches 44 and 50 will be stepped forward until the arms 47 and 55 of these switches, respectively, reach their first contacts whereupon relays 33 and 34 will be connected through the winding of relay 59 to the ground controlled by relay 16. Relay 59 becomes energized and locks through its inner right hand armature and front contact to the ground supplied by the armature of relay 16. At the same time a circuit is established from ground, armature and front contact of relay

16, outer right hand armature and front contact of relay 59, winding of relay 58 to battery and ground. Relay 58 energizes and locks through its armature directly to the ground supplied over the armature of relay 16. As soon, however, as either relay 33 or 34 attracts its armature, a circuit will be extended from ground, the outer right hand armature and front contact of relay 26, conductor 32, normal contact and left hand armature of relay 33 or normal contact and right hand armature of relay 34, and thence through either arm 55 or arm 47 to conductor 60, thereby short-circuiting relay 59 and causing it to become deenergized. With relay 59 deenergized and relay 58 locked, the ground until then supplied over the outer right hand armature and front contact of relay 13 is disconnected and conductor 60 is thereby freed. If this conductor 60 is freed before either relay 33 or 34 has completed its movement, then the marking ground will be maintained by the relay which first became energized. The energization of relay 33 stops further movement of switch 50 and the energization of relay 34 stops further movement of switch 44.

When both relays 33 and 34 have become energized, the ground which was extended to conductor 35 will be disconnected and relay 36 will become deenergized, thereby preventing the possibility of an inaccurate setting of either of such switches as 44 or 50 which may be associated with another speech amplifier such as that assumed to be contained within the rectangle marked 3a.

Thus a line calling over selector 1 will require artificial network 43 to be connected to the speech amplifier and an attenuating network interposed in the line such as that connected between the first contacts of switch 50 traversed by arms 51, 52, 53 and 54.

Should the incoming call have originated in the group of lines served by switch 5, then relay 14 would be energized and a circuit established over the outer right hand armature and front contact of relay 14, through the associated contact and armature of relay 36, to conductor 65, thus marking the second contacts of switches 50 and 44. Hence, a line calling over selector 5 will require an artificial network 42 to be connected to the speech amplifier and an H type attenuating network interposed in the line through the second contacts of switch 50.

The connection having been set up through switches 1 and 12 and thence over conductors 31 to the speech amplifier in the upper part of Fig. 3 will now extend through one of the load distributing switches 66, 67 or others, which are indicated by the downwardly extending conductors at the bottom of Fig. 3. The particular one of these switches to be used will be determined by the level upon which the brushes of switch 12 have been set.

Thus it was assumed that switch 12 was set on its second level resulting in the energization of relay 26. Switch 67 corresponds to the second level of the selector 12 and switch 66 corresponds to the first level thereof. Therefore, a connection will be established from ground, interrupter 61, conductor 62, back contact and armature 68 of relay 69, conductor 70, inner left hand armature and front contact of relay 26, conductor 71, to the winding 72 of the stepping magnet controlling switch 67. The stepping magnet thereupon moves the arms 73 to 78, inclusive, forward step by step. Let it be assumed now that the first contacts traversed by the arms of selector 67 are busy. This condition will be denoted by a ground connection to the winding of relay 79, so that when arm 77 makes connection thereto, relay 69 cannot be operated. A circuit extends from ground, the armature 80 of relay 30, conductor 81, through the lower high resistance and upper low resistance winding of relay 69 in series to arm 77. Therefore, with a ground connection to the winding of relay 79, relay 69 does not become operated and the arms of the switch 67 pass on to their next contacts. Let it be assumed that the second contacts traversed by the arms of this switch 67 are idle. Therefore, the ground connection extended through the windings of relay 69 to switch arm 77 will be extended to the winding of relay 82 and thence to battery and ground. Relay 69 becomes operated and through its innermost lower armature short-circuits its high resistance winding, leaving now only its low resistance winding in series with the winding of relay 82, relay 82 becoming energized. By the operation of relay 69 the circuit of stepping magnet 72 is broken and the switch comes to rest on its second contacts. Through its two upper armatures and front contacts, relay 69 extends the outgoing connections from the speech amplifier to the arms 75 and 76.

Through the arms 73 and 74 the switch 67 now connects an appropriate balancing network 83 to the outgoing end of the speech amplifier and by the operation of relay 82 causes an appropriate attenuating network to be interposed in the line. Thus upon the operation of relay 82 a connection is established from ground, the armature and front contact of relay 82, conductor 84, to the second contact traversed by arm 90 of the line extending switch 85. Upon the energization of relay 69 a circuit is established from ground, interrupter 61, conductor 62, back contact and left hand armature of relay 92, conductor 93, front contact and lowermost armature of relay 69, conductor 94, winding of stepping magnet 95 to battery and ground. The stepping magnet 95 under control of interrupter 61 moves the arms of switch 85 to the contact marked in the bank traversed by 130

arm 90 whereupon relay 92 becomes operated and opening the circuit of stepping magnet 95 allows the switch 85 to come to rest whereupon an **H** type attenuating network is interposed between the speech amplifier and the line reached through arms 75 and 76.

Relay 92 closes a circuit from ground, front contact and right hand armature of relay 92, winding of relay 96 to battery and ground. 10 Relay 96 as indicated closes a circuit for energizing the filament circuits of the amplifiers 40 and 41.

Battery and ground connections are extended through the windings of relays 97 and 98, 15 respectively, and thence through the contacts of relay 30 to the talking conductors leading back to the calling line. These relays in turn control battery and ground connections to the conductors leading to the called line so that 20 by proper manipulation of the calling line any automatic switches connected to the called line may be operated.

At the termination of the connection, switches 1 and 12 may be restored in any appropriate manner whereupon relays 13, 16, 26 and 30 will become deenergized. Upon the deenergization of relay 30, relays 33 and 34 will become deenergized and by closing their right and left hand contacts, respectively, will 25 connect the interrupter 61 through the switch arms 56 and 48, respectively, to the stepping magnets 57 and 49, whereupon the switches 50 and 44 will be returned to normal. In a similar manner relay 69 will become deenergized upon the deenergization of relay 26 and a connection will be extended from the interrupter 61 through the armature 68 and arm 78 to stepping magnet 72 whereupon switch 67 will be returned to normal. Upon the deenergization of relay 82, the ground will be removed from the winding of relay 92 and this will close a circuit for the energization 40 of stepping magnet 95, whereupon switch 85 will be returned to normal.

Fig. 2a represents an organization of relays similar to those shown in the upper part of Fig. 2 and Fig. 3a represents an organization of switches, speech amplifiers etc., similar to that shown in the remainder of Fig. 3. It will be noted that switches 66 and 67 show multiple taps to the conductors outgoing from their different bank contacts. It will be understood that the switches in Fig. 3a, for 50 instance, corresponding to switches 66 and 67, will have their contact banks multiplied to the contact banks of switches 66 and 67.

What is claimed is:

1. In a telephone system, lines of different 55 characteristics, repeaters, automatic switches for establishing connections from said lines to said repeaters, means for adjusting said repeaters in accordance with the characteristics of said lines, and means comprising a plurality of relays commonly associated with said

automatic switches for selectively operating said first means.

2. In a telephone system, lines of different characteristics, repeaters, automatic switches for establishing connections from said lines to said repeaters, balancing and attenuating networks for adjusting said repeaters in accordance with the characteristics of said lines, and means comprising a plurality of relays commonly associated with said automatic switches for selectively operating said first means.

3. In a telephone system, lines of different characteristics, repeaters, automatic switches for establishing connections from said lines to said repeaters, means for adjusting said repeaters in accordance with the characteristics of said lines, and means comprising a chain of lock-out relays commonly associated with said automatic switches for selectively operating said first means.

4. In a telephone system, lines of different characteristics, repeaters, a plurality of stages of automatic switches for establishing connections from said lines to said repeaters, means for adjusting said repeaters in accordance with the characteristics of said lines, and means comprising a chain of lock-out relays commonly associated with each said stage of automatic switches for selectively operating said first means.

In witness whereof, we hereunto subscribe our names this 14th day of November, 1928.

WALTER KUSCHE.

RUDOLF DAHMS.

FRITZ PFLEIDERER.
